UNITED STATES PATENT OFFICE.

JOHN STEVENSON, JR., OF PORTOBELLO, SCOTLAND.

FLEXIBLE SUPPORT FOR STREET-LIGHT HANGERS.

SPECIFICATION forming part of Letters Patent No. 787,410, dated April 18, 1905.

Application filed February 18, 1904. Serial No. 194,202.

To all whom it may concern:

Be it known that I, JOHN STEVENSON, Jr., electrical engineer, a subject of the King of Great Britain, residing at 3 Durham road, Portobello, Scotland, have invented Flexible Supports for Street-Light Hangers, of which the following is a specification.

My invention relates to cable-supporting means for cables which in the performance of their function are caused to pass through curved or irregular-shaped inclosures or passages wherein it is desirable to maintain the said moving cables out of contact with the stationary parts to protect said cables from undue wear.

My invention in its preferred embodiment includes a flexible supporting structure adapted to be bodily inserted and preferably anchored in an irregular tubular or open passage through which a cable is caused to pass, said structure having means whereby said rope or cable is supported in a manner to minimize frictional contact of said cable therewith.

One utility of my invention is in connection with supporting mechanism or poles for street-lamps, wherein it is customary to thread the supporting-cable of the lamp through a curved or swannecked portion of the pole, from the mouth of which one end of the cable passes and is connected with the lamp, said pole being equipped with means connected with the cable, whereby said lamp or other load may be raised and lowered. In structures of this nature it is desirable that the supporting-cable should be maintained out of contact with the pole to enable the operator to raise and lower the lamp with comparative ease and also to prevent the cable from being unduly worn. To effect a support of this nature for the cable, I desirably provide a flexible link-chain structure adapted to conform to varying contours of poles, which structure is desirably provided with antifriction mechanism directly engaging the supporting-cable of a lamp or other load throughout the irregular passage through which said cable moves, said support also engaging the supply-cables at a plurality of points, thereby maintaining said cables out of contact

with the pole throughout the curved portions thereof.

My invention in its preferred embodiment also includes supporting means whereby electric conductors supplying said lamp may be supported in a manner to prevent contact of the same with the internal wall of the pole and also with the supporting-cable of a lamp.

My invention will be more fully described by reference to the accompanying drawings and will be more particularly pointed out in the appended claims.

Figure 1 illustrates the swanneck or curve portion of a lamp column or post, showing the device of my invention in connection therewith. Fig. 2 is a section on line X X of Fig. 1. Fig. 3 is a section on line Y Y of Fig. 1. Fig. 4 is a view of a blank from which are formed members of the flexible supporting structure. Figs. 5 and 6 are side and end elevations of the blank after the same has been pressed into the desired form.

Like characters of reference designate similar parts throughout the different figures of the drawings.

My invention in the embodiment shown comprises a composite link-chain structure *y*, desirably formed of component link members united by rivets. The swannecked or curved portion of a supporting-pole *x* is illustrated, and there are also shown lamp supporting and supplying cables. A cable *l*, to which a lamp (not shown) may be attached, is shown as passing through the pole *x* and located substantially centrally with respect to electric supply-cables *i i* and *g*. The flexible chain *y*, upon which said cables are supported, is desirably provided with antifriction-rollers *O*, spaced apart from each other, upon which rollers the cable *l* is desirably trained. Lateral supports *e* are provided for the supply-cables *i*, and a centrally-disposed recess is preferably formed to accommodate the cable *g*. The construction of the cable-supporting sections of said flexible chain *y* will be understood by reference to Figs. 4, 5, and 6, of which Fig. 4 illustrates a blank from which the chain portions carrying the cable-supports are formed. Said sup-

porting-sections desirably consist of blanks of stamped metal a , having endwise-tapering projections c extending in opposite directions from the body portion of the blank and 5 preferably in planes angular with respect to each other. Said projections c of each supporting-section are desirably united to form a continuous structure by means of link-sections k , which are desirably riveted to said 10 projections c at a^3 in a manner to form a hinged juncture. The cable-supporting sections are preferably assembled by uniting the formed blanks a adjacent to each other by means of connecting-rivets a^{14} passing through 15 the plates a near their upper ends and serving to space said links apart from each other. Said links are held spaced apart near their lower ends by means of the shafts of the rollers o , whose ends are journaled in said plates 20 a . A partition b is supported on the rivets a^{14} , which forms, with the walls f , the recess for the cable g . The lateral supports for the cables i are formed by integral pieces e , projecting from the plates a and centrally disposed with respect thereto. Said projections 25 e , as shown, are bent upwardly and outwardly, thereby forming a curved seat for the cables i , as clearly seen in Fig. 2. I desirably provide the said projections e with rounded 30 flanges, which are shown rounded in order to present to the cables i a smooth and even surface when the same are caused to move by the raising and lowering of the lamp or other load attached to the cable l . 35 It will be seen by the structure just described that the supporting-cable l and the conducting-cables i and g are separated from each other and that it would be impossible for the said cables during the raising and lowering of a lamp or weight to come in contact 40 with each other or with the inner wall of the pole x , thereby insuring protection to the insulation of said cables g and i . It will be seen from the foregoing that a 45 flexible cable-supporting structure of this nature will readily accommodate itself to curved or irregular-shaped passages and that the form herein shown is capable of being used without alteration in various-shaped 50 poles or other structures. This is a great practical advantage, since it avoids the necessity of manufacturing special supports for varying forms and styles of lamp-posts and other structures in which this support 55 may be used. It will be obvious from the foregoing that inasmuch as a support of this nature need coöperate with the cables only during their passage through irregular or curved structures that the support is most 60 desirably and generally anchored therein in order that the movement of the supporting and conducting cables will not alter its position. To this end I desirably provide terminating sections m and p , which are 65 adapted to be anchored by means of bolts m'

and p' , which desirably pass through the wall of the pole x . It will be noted that a cable structure of this nature is capable of being lengthened or shortened to suit the length of the curved or irregular passages in 70 which it is located by adding or disconnecting link-sections. When the desired length is obtained, it is merely necessary to attach the terminals m and p , as clearly shown in Fig. 1. Said terminal m is desirably equipped 75 with apertures m^2 for the passage of the three cables i , i , and g , said apertures being located in a manner to spread the cables and prevent them from coming in contact with the supporting-cable l . 80

While I have herein shown and described a specific form of my invention, it will be obvious that changes may readily be made without departing from the spirit of the invention. 85

What I claim, and desire to secure by Letters Patent, is—

1. In a street-lamp hanger the combination with a pole, of a lamp-supporting cable, lamp-conducting cables, and a flexible support for said supporting and conducting cables including a link chain having rollers for said supporting-cable, said chain having lateral supports for said conducting-cables. 90

2. A link structure comprising lateral 95 stamped members having tapered end projections extending in angular planes with respect to each other, top pieces projecting up and centrally disposed with respect to said tapered projections, bottom pieces bent upon themselves to form cable-supports, means whereby said lateral members may be fastened together, and connecting-links joined to said tapering end projections to form a chain. 100

3. A link structure comprising lateral members having end projections, top pieces projecting upward from said lateral members, bottom pieces bent upon themselves to form cable-supports, means securing said lateral members together, and connecting-links uniting said end projections to form a chain. 110

4. A chain-link comprising lateral members, each member being made from a blank having end pieces projecting in angular planes with respect to each other, a top piece projecting up centrally from said plate, a bottom piece bent in an upward and inward direction, and means whereby said lateral members are fastened together. 115

5. In a street-lamp hanger, the combination with a hollow pole having a curved or irregular-shaped portion, a link chain extending throughout and supported in said curved portion of the pole, and rollers rotatably mounted in said chain and spaced apart at intervals throughout its length, said rollers being adapted to carry a traveling supporting-cable. 120

6. In a street-lamp hanger, the combina- 125

tion with a pole having a curved or irregular-shaped portion, a link chain supported in and anchored upon said curved portion of the pole, and rollers rotatably mounted in said chain and adapted to carry a traveling supporting-cable.

7. In a street-lamp hanger, the combination with a pole having a curved or irregular-shaped portion, a link chain supported by and anchored in said curved portion of the pole and antifriction mechanism carried by said chain, said mechanism directly supporting a traveling cable.

8. A flexible support for traveling cables, comprising a chain composed of separate

links, and rollers mounted thereon for guiding the cable, said chain being provided with fastening-links for anchoring it to a stationary support.

9. A flexible support for traveling cables, comprising a chain composed of separate links, means carried by said chain for guiding the cables, and fastening means for securing said chain to a stationary support.

Signed at Glasgow, Scotland, this 30th day of January, 1904.

JOHN STEVENSON, JUNR.
